UNITED STATES PATENT OFFICE.

SAMUEL J. LARGE, OF BRISTOL, CONNECTICUT, ASSIGNOR TO AMERICAN SILVER COMPANY, OF BRISTOL, CONNECTICUT, A CORPORATION.

DESIGN FOR A HANDLE OF SPOONS OR SIMILAR ARTICLES.

No. 37,942.

Specification for Design.

Patented April 10, 1906.

Application filed February 14, 1906. Serial No. 301,083. Term of patent 7 years

To all whom it may concern:

Be it known that I, SAMUEL J. LARGE, a citizen of the United States, residing at Bristol, in the county of Hartford and State of Connecticut, have invented a new, original, and ornamental Design for the Handle of a Spoon or Similar Article, of which the following is a specification, reference being had to the accompanying drawings, forming part thereof.

Figures 1 and 2 are respectively obverse and reverse views of the handle of a spoon or similar article.

I claim—

The ornamental design for the handle of a spoon or similar article, as shown.

SAMUEL J. LARGE.
